Primary Examiner — Llorellys Martinez-Rivera

(74) *Attorney, Agent, or Firm* — Law Office of Paul B. Johnson; Paul B. Johnson

(57) **CLAIM**

The ornamental design for a ring, as shown and described.

DESCRIPTION

FIG. 1 is a front, top and right perspective view of a ring showing our new design;

FIG. 2 is an exploded front, top and right perspective view thereof;

FIG. 3 is a front, bottom and left perspective view thereof;

FIG. 4 is an exploded front, bottom and left perspective view thereof;

FIG. 5 is a top view thereof, the bottom, left side and right side views being identical thereto;

FIG. 6 is a front view thereof;

FIG. 7 is a rear view thereof;

FIG. 8 is a top view of the inner portion of the ring in FIG. 1, the bottom, left side and right side views being identical thereto;

FIG. 9 is a front view of the inner portion of the ring in FIG. 1;

FIG. 10 is a rear view of the inner portion of the ring in FIG. 1;

FIG. 11 is a front view of the outer portion of the ring in FIG. 1, the rear view being identical thereto; and,

FIG. 12 is a top cross-sectional view of the ring in FIG. 1, taken along lines 12-12 in FIG. 6.

The broken lines in the drawings represent portions of the ring and form no part of the claimed design.

1 Claim, 9 Drawing Sheets
